UNITED STATES PATENT OFFICE.

ANDREW E. MARKWELL, OF FORT WORTH, TEXAS, ASSIGNOR, BY DIRECT AND MESNE ASSIGNMENTS, OF THREE-FOURTHS TO CHARLES W. HANSON, OF FORT WORTH, TEXAS, AND ONE-FOURTH TO A. D. EVANS, OF TARRANT COUNTY, TEXAS, AND GEO. W. ITTNER, OF ST. LOUIS, MISSOURI.

MATRIX BROACH-MOLDING DEVICE.

1,218,680.

Specification of Letters Patent.

Patented Mar. 13, 1917.

Application filed August 14, 1913, Serial No. 784,693. Renewed August 7, 1916. Serial No. 113,607.

To all whom it may concern:

Be it known that I, ANDREW E. MARKWELL, a citizen of the United States, residing at Fort Worth, in the county of Tarrant and 5 State of Texas, have invented certain new and useful Improvements in Matrix Broach-Molding Devices, of which the following is a specification.

My invention relates to matrix molding devices for use in linotype or intertype or line casting machines, and the object is to provide devices for use in combination with matrix molding devices for molding holes of predetermined design through the beveled 10 faces of type high cross rules at right angles to the rules. The purpose of this construction is to prepare cross-rules which are adapted to print cross-lines without any break in the cross-lines at the point of crossing. Another advantage sought is to prepare devices which can be set up and used in linotype or intertype or line casting machines without preparing new designs of 15 machines. Other objects and advantages 20 will be fully explained in the following description and more particularly pointed out in the claims.

Reference is had to the accompanying drawings which form a part of this application.

Figure 1 is an edge view or plan view of a matrix, showing the location of the improvements mounted therein. Fig. 2 is a side elevation of a matrix, showing the location of the improved forming devices. Fig. 3 is a side elevation of a matrix, with a part of the inclosing plate broken away to expose the forming devices. Figs. 4 and 4^a are respectively a side elevation and an end elevation of one of the hole forming devices. Fig. 5 shows a side and an end elevation of a slug, the side elevation showing the hole through the cross-rule.

Similar characters of reference are used 45 to indicate the same parts throughout the several views.

A matrix block 1 is provided with a plate 2 which may be riveted to the block 1. Cavities 9 are formed in the block 1 and forming devices 3 and 4 are pivotally mounted in the cavities and these formers have beveled ends 5. The ends 5 terminate in close proximity to each other and practically against each

other. The object is to make the apex of the rule on the slug and the apex of the rule 55 which is to be inserted through the hole in the slug rule come together practically in a point. The formers 3 and 4 lie normally with their upper or outer surfaces flush with the outer surface of the edge of the matrix 1. 60 The formers 3 and 4 have shoulders 10 at their rear ends and springs 6 and 7 are secured at 12 in the block 1 and press outwardly against the shoulders 10 so that the formers 3 and 4 are held yieldingly in their 65 normal positions and will yield to the positions of the dotted outline in Fig. 3 to allow the removal of the casting or slug through the rule of which the hole has been cast. When the slug is drawn away from the 70 matrix, the parts 5 of the formers will be drawn outwardly by the slug and as soon as released, the formers will be forced back within the block 1 in their normal positions. The slugs can thus be formed with holes 8 75 through the rules 11 on the slugs. The rules on the slugs may be of any suitable design provided they are type high. The holes 8 should conform in cross-section to the cross-section of the rule which is to be thrust 80 through the holes 8.

The matrix 1 and the plate 2 have cross grooves 13 through the top or upper part leading toward the forming devices 3 and 4 which have the beveled surfaces 5—5.

What I claim, is:

1. Matrix molding devices comprising a body provided with longitudinal cavities in the edge thereof, a pair of forming devices mounted in said cavity and having the outer 90 surfaces flush with the edge of said body and having bearings for pivot bolts, pivot bolts holding said forming devices in said cavity, and springs for drawing said forming devices back into said cavity.

2. Matrix molding devices comprising a body having longitudinal cavities therein in one edge, a pair of forming devices pivotally mounted in said cavities and having their meeting ends triangular in cross-section and 100 having extensions beyond the pivotal connections, and springs bearing against the undersides of said extensions.

3. Matrix molding devices having a pair of forming devices pivotally mounted there- 105 in and having openings extending inwardly

toward said forming devices and springs holding said forming devices normally within said matrix.

4. Matrix molding devices comprising a matrix, forming devices having beveled under surfaces and pivotally mounted in said matrix and having backwardly extending shoulders, and springs attached to said matrix and engaging said shoulders to hold said forming devices normally within said matrix.

5. Matrix molding devices having a matrix provided with a longitudinal cavity therein, forming devices having beveled

under surfaces at their meeting ends and pivotally mounted in said cavity and having backwardly extending shoulders, and springs attached to said matrix and pressing outwardly against said shoulders, said matrix having grooves extending through the sides to said forming devices.

In testimony whereof, I set my hand in the presence of two witnesses, this 2nd day of August, 1913.

ANDREW E. MARKWELL.
